HENRIK THORE CEDERGREN, OF STOCKHOLM, SWEDEN.

SIGNALING DEVICE FOR TELEPHONE SYSTEMS.

SPECIFICATION forming part of Letters Patent No. 772,782, dated October 18, 1904.

Application filed January 28, 1902. Serial No. 91,576. (No model.)

To all whom it may concern:

Be it known that I, HENRIK THORE CEDERGREN, a subject of the King of Sweden and Norway, residing in Stockholm, Sweden, have 5 invented certain new and useful Improvements in Signaling Devices for Telephone Systems, of which the following is a specification.

This invention relates to signaling means employed in telephone systems wherein a central battery is employed and wherein a line-relay controlled by the subscriber is energized as long as the line of the subscriber is engaged. The characteristic feature of the invention resides in the fact that the said relay controls 15 the calling-signal, as well as the clearing-out signal, in such a manner that a current passing through the calling-signal will be closed by the armature of the said relay at the calling of the exchange—that is, as the subscriber 20 removes the telephone from the switch-hook—and that when the current through the same relay is interrupted as the subscriber hangs up the telephone on the hook and the armature then returns to its normal position the 25 relay will effect such an alteration of the current passing through a clearing-out relay inserted in the third cord conductor that the relay last mentioned puts the clearing-out signal into operation. By arranging the clearing-out relay in the third cord conductor a considerable diminishing of the load of the conversation-transmitting current is effected.

The invention is illustrated diagrammatically in the accompanying drawing, wherein 35 the same is shown applied to a telephone system provided with a central battery and with inductive resistances inserted between each line and the battery.

A and B designate two subscribers' apparatus, and L' L² are two lines leading to the exchange, where connections are made, respectively, to the branched jacks J' and J². Inductive resistances I I' and I² I² are inserted 40 between the main respective branches of said lines, the other ends of the resistances being connected with the respective terminals of the battery B' by means of wires 1 2 and 3 4 in the manner shown in the drawing.

P' P² are two plugs belonging to the same 45 pair of cords. In the line conductors of the

cords are inserted condensers K' K². The resistances I' and I² are arranged as relays.

The connections in the subscriber's instrument are of the well-known type where when speaking is not going on the bell and a condenser are placed in the line-circuit, the latter being thus interrupted for continuous currents, but when speaking is going on the transmitter and the receiver are put in series in the line-circuit, said circuit being closed. 55

As seen from the drawing, the arrangements of the cord-circuit, as well as of each subscriber's line, are entirely symmetrical. For that reason it is sufficient in the following description of the invention only to explain one side of said cord-circuit and one subscriber's line. 60

As seen from the drawing, the armature a' of the relay I' bears when excited upon two contacts k' k². A wire 5 connects the contact k² with the receiving-stud k³ for the armature a³ of the relay R³. The signal S³, which may be of any suitable kind, is connected with the armature a³ at one side and with the battery B' at the other. The contact k' is joined to 70 the relay R³ by means of a wire 6, and a wire 7 leads from the other end of said relay to the test-springs f' of the line. The armature a' is connected with the other pole of the battery B' by means of a wire 8, said pole being 75 connected to earth. In the third cord conductor a relay R² is inserted, said conductor being also connected with the battery. The armature a² of said relay closes and breaks the circuit through the clearing-out signal S² 80 when the plug P' is lifted from the keyboard, and thus the contact p', controlled by said plug, is closed. As the drawing is diagrammatic, it may be of advantage to explain that the contact p' is hinged and has a spring 85 which tends to hold its lower end or tail in contact with a terminal contact-piece p², but when the plug P' is moved down in front of the head on p' the connection with p² is broken.

The operation of the invention is as follows: In order to call the exchange, the subscriber removes the telephone from the switch-hook. Current then passes from the battery B' through the wire 2, the relay I', one branch 90 of the subscriber's line, the switch-hook, the 95

too

receiver and the transmitter, the other branch of the subscriber's line, the inductive resistance I , and the wire 1 back to the battery. The relay I' is then excited—*i. e.*, it attracts the armature a' . A current-circuit is now closed through the wire 9, the lamp S^3 , the wire 10, the armature a^3 , the contact k^3 , the wire 5, the contact k^2 , the armature a' , and the wire 8. The lighting of the lamp S^3 indicates the call. Now the operator inserts the plug P' into the proper jack J , whereby the following circuit is established: the battery B' , the wires 11 12 13, the relay R^2 , the wire 14, the plug P' , the test-spring and the spring f' , the wire 7, the relay R^3 , the wire 6, the contact k' , the armature a , and the wire 8. The relay R^3 now attracts its armature a' , whereby the circuit is broken through the calling-signal S^2 and the lamp is extinguished. At the same time the relay R^2 attracts its armature a^2 . The circuit through the signal S^2 , closed by the contact p' at p^2 as soon as the plug was lifted from the keyboard, is thus broken by the armature a^2 . In consequence whereof the lamp S^2 will not be lighted. At the end of the conversation the subscriber hangs up the telephone on the hook. The current through the relay I' is thereby interrupted. The armature of the same returns to its normal position and breaks in its turn the circuit through the relay R^2 . The contact k^4 is thereby closed, and the lamp S^2 will be lighted and indicate that disconnection is to be made. Consequently the operator removes the plug from the spring-jack. When the plug has been returned to the keyboard, the contact p' is interrupted and the lamp S^2 extinguished.

In the drawing the signals are shown as 40 incandescent lamps; but evidently any other suitable kind of signals may be used, and in the practical execution of the invention the arrangements shown in the drawing may be

modified in many respects without exceeding the limits of the invention defined in the 45 claims.

Having thus described my invention, I claim—

1. In a signaling means for the purpose specified, the combination with a relay I' , in 50 the subscriber's circuit, the relay R^3 connected with the test-line 7, the said test-line, the relay R^2 in the cord-circuit of the system and so connected that the insertion of the plug of the cord in its corresponding jack connects 55 the relay R^2 in series with the relay R^3 through the test-line 7, the clearing-out signal S^2 , its circuit, and means whereby the relay R^2 controls the last-named circuit, said relay R^2 being connected during the conversation, with the 60 armature a' of the relay I' so that the contact of relay R^2 will be closed when at the end of the conversation the relay I' becomes inactive and the circuit through its armature a' becomes broken. 65

2. In a signaling means for the purpose specified, the combination with the relay I' in the subscriber's circuit, the relay R^3 connected with the test-line 7, the said test-line the relay R^2 in the cord-circuit of the system and 70 so connected that the insertion of the plug of the cord in its corresponding jack connects the relay R^2 in series with the relay R^3 and the armature a' of the relay I' , the clearing-out signal S^2 , its circuit, and means whereby 75 the relay R^2 , when excited, breaks the last-named circuit, said circuit being closed when the relay I' becomes inactive. 75

In witness whereof I have hereunto signed my name in the presence of two subscribing 80 witnesses.

HENRIK THORE CEDERGREN.
